COOLING RECEPTACLE

James I. Kushima, Ewa, Territory of Hawaii

Application January 9, 1939, Serial No. 249,999

1 Claim. (Cl. 62—142)

This invention relates to improvements in receptacles, such as drinking cups, fruit or punch bowls, and the like.

It is an object of the invention to provide a receptacle having an ice chamber formed in the center of the receptacle whereby the contents of the receptacle may be cooled without the contents coming in direct contact with the ice.

A further object of the invention resides in providing a receptacle of the above-mentioned character which is simple and durable in construction, efficient in operation, ornamental in appearance, and inexpensive to manufacture.

Other objects and advantages of the invention will be apparent during the course of the following description.

In the accompanying drawing forming a part of this specification, and in which like numerals are employed to designate like parts throughout the same:

Figure 1 is a sectional view of a punch bowl, showing the ice chamber partly in section and partly in side elevation.

Figure 2 is a top plan view of the punch bowl, showing the ice chamber partly in horizontal section,

Figure 3 is a vertical section of a drinking cup, taken on the line 3—3 of Figure 4, with the ice chamber embodied in its construction and partly in longitudinal section, and

Figure 4 is a top plan view of the drinking cup.

In the drawing, wherein for the purpose of illustration I have shown a preferred embodiment of my invention, the numeral 5 denotes a punch or fruit bowl which may be constructed of glass or other suitable material. The bowl shown is semi-circular shape in vertical cross section and has an inclined flange 6 depending from the bottom forming a base for supporting the bowl. A vertical tube 7 is formed integral with the bottom of the bowl and extends upwardly in the center of the bowl with its upper end terminating in an enlarged dome-shaped head 8. The lower end of the tube extends through the bottom and is provided with exterior screw threads 9 to receive the screw cap 10 which closes the lower end. The outer wall of the tube 7 is polygonal shape, providing a series of spaced vertical ridges 11 and the outer surface of the dome-shaped head 8 is provided with a series of spaced spiral ridges 12. The ridges 11 and 12 serve to agitate the liquid in the bowl, when stirred.

In Figures 3 and 4, a glass drinking cup 13 is

shown, having a central vertical tube 14 forming an ice chamber. The tube 14 is tapered towards its upper end, which is rounded, as at 15, and the outer side wall of the tube is provided with spaced spiral ridges 16 which serve to agitate the liquid in the cup, when stirred. The bottom 17 of the cup is spaced upwardly from the lower end of the cup and the lower end of the tube 14 extends through the bottom and has exterior screw threads 18 to receive a screw cap 19 closing the lower end of the tube.

In operation, the ice chamber of the bowl shown in Figure 1, or the drinking cup shown in Figure 3, is filled with ice which is placed in the chamber by removing the screw caps closing the lower end of the tubes forming the ice chambers. With the ice chambers filled with ice, the liquid contained within the bowl or drinking cup will be cooled by contact with the ice chamber without the liquid's coming into direct contact with the ice. This prevents diluting of the liquid. The ridges provided on the outer wall of the ice chamber facilitate cooling of the liquid by increasing the agitation of the liquid when stirred. While the receptacles are primarily intended for cooling liquids to be consumed, the bowl may also be employed to hold fruit, the ice chamber serving to keep the fruit in a refrigerated condition to prevent spoilage. In practice, it has been found that the best results are obtained if the capacity of the ice chamber is equal to one-third the capacity of the bowl.

It is to be understood that the forms of my invention herein shown and described are to be taken as preferred examples of the same and that certain changes in the shape, size, and arrangement of the parts may be made without departing from the spirit of the invention or the scope of the subjoined claim.

Having thus described my invention, I claim:

A cooling device comprising a receptacle, a central refrigerant chamber extending upwardly from the bottom of the receptacle and formed integral therewith, the bottom of said chamber being open and surrounded by a screw-threaded collar beneath the bottom of said receptacle, a series of spaced raised longitudinal ridges formed on the outer wall of said chamber, said ridges being tapered to a sharp edge, and a screw cap for engagement with the screw-threaded collar to close the open end of said chamber.

JAMES I. KUSHIMA.
